ROSCOE C. IDDINGS, OF DAYTON, OHIO.

FIRE EXTINGUISHER.

1,390,035.

Specification of Letters Patent.

Patented Sept. 6, 1921.

Application filed April 10, 1919. Serial No. 288,933.

To all whom it may concern:

Be it known that I, ROSCOE C. IDDINGS, residing at Dayton, Ohio, have invented certain new and useful Improvements in Fire Extinguishers, of which the following is a full, clear, and exact description.

My present invention is an improvement over the device shown in my pending application, Serial No. 148,309, and has for its principal object to render devices of this class more reliable and certain to operate properly in an emergency. Fire extinguishers are essentially emergency devices, which, being rarely used are liable to be found unfit for use when needed, and to obviate this as far as possible it is important to adopt every available expedient whereby deterioration in any form may be prevented, and that such deterioration as can not be prevented may be rendered innocuous. In construction my present invention resembles the one shown in the above mentioned application, among other things in that it has a pump with which to store air under pressure in the receiver and has valves or seals that close the outlets and prevent escape of the air or the extinguishing fluid; also in that these valves are operated by rotary motion of the pump piston, the same movement operating locking mechanism which holds the piston in its inner position; also in that by a partial turn of the piston in either direction a steady stream of fluid, expelled by the compressed air, may be played upon the fire without actuating the pump, and without turning the piston enough to unlock it. In the present device I employ metal-to-metal valves or "seals" where in the former one I used cork or some other suitable non-metallic substance as one element in the seals, and have improved the locking device for the piston. Other improvements, which will be referred to later, not only contribute to the stability of the device but improve its appearance and, what is quite important, reduce the manufacturing cost.

Referring now to the accompanying drawing,

Figure 1 is a transverse sectional view of an extinguisher embodying my improvements;

Fig. 2 is a fragmental view showing certain portions of the pump and valve mechanism in different positions than they occupy in Fig. 1;

Fig. 3 is a fragmental view showing op-

eration of the automatic check valve by rotary movement of the pump piston;

Figs. 4 and 5 are two views of a locking member for preventing reciprocal movement of the pump piston;

Figs. 6 and 7 are views of a guide for the piston rod;

Fig. 8 is a fragmental view showing a modification of the valve mechanism;

Figs. 9 and 10 are diagrammatic views for showing the timing of the valve mechanism.

Within the container 25 is placed a pump comprising a cylinder 26, piston 27, piston rod 28 and handle 29 for operating the pump. At its inner end the rod carries a collar 30, whose inner edge is beveled and adapted to coöperate with a valve seat 31 formed in a casting 32 secured to the end of the cylinder, and form a closure or seal for the pump cylinder. The collar is held in contact with the seat by yielding pressure obtained with the following mechanism:

The outer end of the pump cylinder is secured in a flange 35 which projects from the end piece of the container. A guide 36 slips loosely in the end of the cylinder and has a flange 37 which extends laterally and bears on the ends of the cylinder and flange 35. The outside of the flange is threaded to receive a cap 38; this cap has an aperture 39 in its head through which the piston rod passes, but which is considerably larger in diameter than the rod; the edge of this aperture is provided with a low ridge 40. The handle 29 has a skirted flange 41 that extends out over the cap 38, the skirt encircling the ridge 40. The purpose of this is to shed water and prevent its running down into the cylinder, this being one of the expedients I have devised for maintaining the effectiveness of the extinguisher, even though it be exposed to the elements, as it would be, for example, on the dash of a motor truck. Within the cap 38 is a locking member 42; this member is a sort of sub-cap and its outer end lies in the aperture 39, whereby it is guided. Its inner end

has a flange 43 that extends out to the wall of the cap 38 and acts as a second guide for the member 42. A compression spring 44 confined between this flange and the head of the cap 38 presses the member 42 toward the guide 36. The interior diameter of the locking member is large enough to accommodate a pin 45 which passes through the piston rod, and in addition to a circular ap-

erture in the head, through which the piston rod passes there are two radiating recesses 46 for the passage of the pin 45 when the piston rod is drawn out. On the inside 5 of the head rising from each side of each of these recesses is a spiral cam 47, which cams terminate at notches 48. When the piston rod is in its innermost position it may be rotated in either direction, and when this is 10 done the sides of the pin 45 impinge on two of the cams, according to which way the piston is rotated, and cam the locking member outward in opposition to the spring 44; when the ends of the pin 45 arrive opposite 15 the notches 48 the spring presses the locking member inward until the notches bear against the pin, and by this means a frictional lock is formed which is capable of resisting quite a substantial force tending 20 to turn the handle, while allowing the handle to be turned in either direction when it becomes necessary to do so. It also affords an indication, through the sense of touch, of the position of certain internal parts. This 25 point will be enlarged upon presently. The tension of the spring, acting through the locking member and pin, presses the piston rod inward and holds the beveled face of the collar 30 against the seat 31. In Fig. 1 the 30 piston rod is represented as having been unlocked but not yet withdrawn any, the collar 30 still being on the seat. In Fig. 2 the piston has been withdrawn and is on its in-stroke. The locking member is kept 35 from turning on the cylinder by a tongue 49 on each side of the flange 43, which extend into slots 50 formed in the united flange 35 and cylinder 26. Corresponding notches 51 are cut in the guide member 36.

40 The contents of the container is expelled through one or the other of two flexible tubes 60, a valve chamber 61, tube 62, plug valve 63, tube 64 and a nozzle 65. By means of a gravity operated valve mechanism, 45 which is described in detail in my application above mentioned, the tube 60 that is uppermost is cut off from the discharge passages, so that if its open end is above the level of the contents of the container air 50 will not escape to the nozzle. The plug 66 of the valve 63 has a flat extension 67, which is embraced by the tines of a bifurcated extension 68 on the collar 30 when the piston rod is in its inner position as in Fig. 1. By 55 means of this coupling the valve may be opened and closed by turning the handle 29. The parts are so timed that the valve 63 is open when the piston rod is turned to a position where it can be drawn out; when the 60 rod is turned to locking position, with the pin 45 in the notches 48, the valve is closed and when the operator feels the pin fall into the notches he knows the valve is closed. When the piston is drawn out the collar is uncoupled from the plug, but the parts are so proportioned that the pin enters the recesses 46 in the locking member before the fork 68 reaches the extension 67 and by this means registration of the fork with the extension is insured, so that coupling the collar to the valve cannot present any difficulty.

70 The pump is provided with the usual automatic check valve which comprises a conical valve seat 75, formed in the casting 32, and a spring actuated valve member 76 operating in a chamber 77. To guard against the possibility that the valve might have become stuck from long inaction, corrosion or other causes, I provide means for lifting the valve 75 from its seat as the handle 29 is turned to unlock the piston. This consists of a pin 78, one end of which is adapted to bear against the valve member 76, the other end extending into the cylinder so as to be in 80 the path of the corners of the extension 68. Referring to Fig. 3 it will be seen how as the handle is rotated it engages the pin and cams it outward, the pin in turn lifting the valve from its seat momentarily. In Fig. 3 85 the handle is assumed to be approximately midway between the position it occupies in Fig. 1 and the position it would occupy when locked. Should the valve have become stuck from any cause this will free it 90 so that when the pump is operated it will act properly. In Fig. 2 the piston is assumed to be moving inward and therefore driving air past the check valve, which is 95 consequently open.

100 The piston 27 is mounted on the rod with sufficient freedom so the rod can move endwise therein, this lost motion being limited in one direction by the collar 30 and in the other direction by a collar 85. The piston is provided with the usual leather cup 86, which is kept pressed against the wall of the cylinder by a helical spring 87 coiled inside of the leather. When the rod is moving outward the piston, being retarded by 105 friction in the cylinder, bears against the collar 30; longitudinal grooves 88 in the bore of the piston and radiating grooves 89 on the end that bears against the collar 30, 110 act as ports and allow air to pass the piston as it is drawn outward. On the return of the handle, friction, supplemented by compressed air in the cylinder, again retards the piston and presses it against a leather washer 90 that is interposed between 115 it and the collar 85, which effectually closes the ports 88. By this means a very durable pump is provided and the possibility of the cup leather shrinking and failing to hold the pressure is eliminated by the spring 87, 120 while the ports allow free passage of air past the piston on its idle stroke, making it easy to operate and eliminating the tendency to create a vacuum in the cylinder.

125 To operate my extinguisher it is only nec-

essary to unlock and operate the piston. As it can be unlocked by turning in either direction there is no danger of delay through the operator becoming confused as to which way to turn the handle. As the fluid is discharged by air which has been compressed in the container it is likely to continue running after pumping ceases. To stop the stream then it is only necessary to 5 push the piston clear in and turn it to locked position. Or the operator can stop the stream by placing his finger over the nozzle. A very satisfactory way of using the device is to keep a charge of compressed 10 air in the container, ready to expel the contents as soon as the handle is turned. It is not necessary to turn the handle to full unlocked position, as the area of the valve 63 is such as to afford an adequate passage with 15 20 the valve but little if any more than half open. Operated in this way the collar 30 is kept seated and the seal of the cylinder is effectually maintained. It is to be noted that this seal is supplemental to the check 25 valve, thus affording double security.

In Fig. 8 I show a modified structure, wherein the plug valve is made double, so as to control the discharge and also seal the cylinder. In this structure the plug 95 has, in addition to the port for passage of the fluid another port, 96, for admitting air from the cylinder to the check valve chamber 77. In Figs. 9 and 10 I illustrate the timing of the valve ports to show how the 30 discharge valve can be opened and the fluid discharged without opening the air valve. In Fig. 9 the fluid port is in a position to allow fluid to flow from the tube 62 to tube 63, while the air port, shown in Fig. 10, is not 35 open. In this figure it will be seen that midway between the ports, on each side of the plug 95, there is a depression 97. When the valve is shut off; that is, when the piston is locked in, the spindle 98 of the check 40 valve rests in one of these depressions. When the valve is turned by turning the handle the sides of these recesses engage the conical end of the spindle and cam the valve out, unseating it momentarily. When 45 the valve reaches its open position the end of the spindle projects into the port 95, allowing the valve to function normally.

Having shown and described the preferred embodiment of my invention, and also one modification thereof, I do not wish it understood that the invention is limited to the structures shown, as other modifications may be made within the scope of my claims.

What I claim as novel is as follows:

1. In a fire extinguisher, a pump having a valve seat in the end of the cylinder, a valve member carried by the piston and adapted to coöperate with said seat to close the end of the cylinder, and means for yield- 5 ingly holding said member on said seat,

comprising: a stud projecting laterally from the piston rod, a cam which is engaged and displaced by said stud when the piston is rotated in the cylinder, and a spring whereby the cam is enabled to offer yielding resistance to said displacement. 70

2. In a fire extinguisher, a container having a discharge tube, a plug valve therein, a pump having a valve seat in the end of the cylinder, a valve member carried by the piston and adapted to coöperate with said seat and close the end of the cylinder, means for pressing the piston toward the end of the cylinder so as to keep said valve member on said seat, said means remaining 75 effective while the piston is rotated a limited distance, and means whereby when the cylinder is thus closed the piston is coupled to the plug of said plug valve, so that the valve can be opened or closed by turning the piston. 80

3. In a fire extinguisher, a container having a discharge tube, a plug valve therein, a pump having a valve seat in the end of the cylinder, a valve member carried by the piston and adapted to coöperate with said seat and close the end of the cylinder, means for pressing the piston toward the end of the cylinder so as to keep said valve member on said seat, said means remaining effective 90 while the piston is rotated a limited distance, means whereby when the cylinder is thus closed the piston is coupled to the plug of said plug valve, so that the valve can be opened or closed by turning the piston, and 95 means for preventing withdrawal of the piston from or its return to the coupling position except when it is in a predetermined angular position. 100

4. In a fire extinguisher, a liquid container having a discharge nozzle, a pump comprising a cylinder and a reciprocal piston, locking means for locking the piston at a given end of the cylinder when the apparatus is not being used, a rotary valve 105 for preventing discharge of liquid through said nozzle, said valve being located adjacent the end of the pump cylinder at which the piston resides when locked, and means for rotating said valve by rotary motion of the 110 piston when the piston is in said position of disuse. 115

5. In a fire extinguisher, a liquid container having a discharge nozzle, a pump comprising a cylinder, a piston rod with an 120 operating handle at one end and a piston at the other, a rotary valve adjacent the end of the cylinder which is remote from said handle, and in axial alinement with the cylinder, and means for coupling the piston 125 to the valve when the piston is at the end of its inward stroke, so the valve can be rotated by rotary motion of the piston.

6. In a fire extinguisher, a reciprocating pump, a valve having a revoluble element 130

- 4
- whose axis coincides with that of the pump; coupling means whereby when the piston reaches its inner position it is coupled to said element, so that said element can be rotated by turning the piston, and means for preventing withdrawal of the piston from or its return to the coupling position except when it is in a predetermined angular position.
- 10 7. In a fire extinguisher, a reciprocating pump, a valve having a revolute element whose axis coincides with that of the pump; coupling means whereby when the piston reaches its inner position it is coupled to said element so that said element can be rotated by turning the piston, means for preventing withdrawal of the piston from or its return to the coupling position except when it is in a predetermined angular position, and means for retaining the piston in a position which prevents its withdrawal, said means being adapted to yield to a substantial force but offering enough resistance to prevent accidental movement of the piston.
- 15 8. In a fire extinguisher, a reciprocating pump having an automatic check valve, means for positively opening said valve and then allowing it to close itself before starting to operate the pump, and means for insuring that the valve will be thus treated before operation of the pump is begun.
9. In a fire extinguisher, a container having a discharge tube, a plug valve in said tube whereby the discharge may be cut off and controlled, a reciprocating pump having an automatic check valve, means for turning the plug valve on or off by rotary movement of the pump piston, and means for positively opening said check valve and allowing it to close, said means being actuated by the same movement of the piston whereby the plug valve is actuated.
- 10 10. In a fire extinguisher, a container, means, comprising a reciprocating pump, for discharging the contents from the container, and means for locking the piston of the pump to prevent its reciprocal movement, comprising: a cap secured to the end of the cylinder, a member within the cap provided with spiral cams, a pin inserted crosswise in the piston rod, the sides of which pin engage the cams when the piston rod is rotated and move said member toward the cap, a spring confined between the cap and said member adapted to yieldingly resist said movement by the member, said member having notches which said cams lead to, into which the pin drops and whereby longitudinal movement by the piston is prevented and rotary movement considerably opposed.
- 11 11. In a fire extinguisher, a liquid container, a pump therein, said pump comprising a cylinder, a piston and a casting that forms a head for the cylinder, said casting having an extension which is bored for and contains a rotary valve, said valve being in axial alinement with the cylinder; a discharge tube leading from one side and a supply tube leading to the opposite side of said extension, said valve being adapted to connect said tubes or cut off communication between them; and means for rotating the valve by rotary motion of the pump piston.
